UNITED STATES PATENT OFFICE.

MERTON A. STEELMAN, OF VINELAND, NEW JERSEY; ANNA MARTHA STEELMAN, AD-
MINISTRATRIX OF SAID MERTON A. STEELMAN, DECEASED, ASSIGNOR TO HART-
FORD-EMPIRE COMPANY, OF HARTFORD, CONNECTICUT, A CORPORATION OF DELA-
WARE.

DEVICE FOR DISCHARGING MOLTEN MATERIAL.

Application filed June 6, 1916, Serial No. 101,878. Renewed October 29, 1924.

My invention relates to devices for discharging molten material (say, glass) from a furnace, and has been particularly designed for use in conjunction with machines 5 for making bottles or other receptacles, where it is desired to withdraw from the furnace small measured quantities of molten glass in quick succession and transfer such small quantities to molds or other receivers, 10 for the purpose of forming the amount of molten glass withdrawn each time into a bottle or other receptacle. The main purpose of my invention is to transfer the molten glass from the furnace in such a way as to 15 effectively keep the glass hot and of proper viscosity, and to prevent it from becoming thick and clogging up the passages of the apparatus. Another object of the invention is to insure a thorough emptying of said 20 passages when it is no longer desired to discharge glass from the apparatus and preferably to provide for the separate discharge of the material remaining in the passages of the apparatus at the end of the operation. 25 Another feature of the invention consists in special means for cutting off and properly directing and to some extent shaping the molten material on its way to the receiver. Other features will appear from the description 30 following hereinafter, and the novelty will be pointed out in the appended claims.

In the accompanying drawings, forming part of this specification, Fig. 1 is an elevation of my apparatus, shown in connection 35 with a glass furnace; Fig. 2 is a horizontal section taken on line 2—2 of Fig. 1, and shown on an enlarged scale; Fig. 3 is a central vertical section through my apparatus, taken on line 3—3 of Fig. 4, certain parts 40 which are shown in detail in other views, being omitted; Figs. 4 and 5 are a horizontal section and a vertical section respectively taken on lines 4—4 and 5—5 of Fig. 3; Fig. 6 is a partial vertical section taken on line 45 6—6 of Fig. 7, and in the same plane as Fig. 3, but showing the knife carrier controlling the glass flow in the position of closing the nozzle outlet; Fig. 7 is a vertical section taken at right angles to Fig. 6 in a plane indicated by line 7—7 in Fig. 6, but showing 50 the knife carrier in a position in which it uncovers the nozzle opening; Figs. 8 and 9 are sections taken on lines 8—8 and 9—9 re-

spectively of Fig. 6, and illustrating certain details; Fig. 9^a shows a modification of the 55 device illustrated in Fig. 9; Fig. 10 shows, in conjunction with Figs. 1, 2 and 7, the mechanism for controlling the position of the knife carrier; and thereby the glass flow; Figs. 11 and 12 are sections through one of 60 the valves shown in Fig. 10, Fig. 11 being taken on line 11—11 of Fig. 12, and Fig. 12 on line 12—12 of Fig. 11; Fig. 13 is a partial bottom view, looking in the direction of the arrow 13 in Fig. 1; Fig. 14 is a bottom 65 view of the knife carrier and the knife; Fig. 15 is a central section through said carrier and knife, taken on line 15—15 of Fig. 14; and Figs. 16 and 17 are diagrammatic views 70 illustrating the operation of the knife. 70

Referring now to the drawings, and particularly to Figs. 1, 3, 4 and 5, the glass furnace 18, of any approved construction, has in its wall an opening or outlet consisting of an upper comparatively wide portion 18' and a lower comparatively narrow portion or channel 18'' leading into an intermediate chamber 19 built of fireclay or other fire-proof material and attached to the furnace. This chamber 19 rests on a bottom plate 20 having a flange 20' extending all the way around the lower portion of the chamber 19; the bottom plate 20 and the chamber 19 are supported from the glass furnace, as will be described below. The channel 18'' communicates with an inclined supply channel 21 leading into an upright discharge chamber 22 preferably of circular cross section, both arranged within the chamber 19. The roof of the inclined channel 21 is open to the chamber 19 adjacent to the channel 18''. A cover 22' normally closes the upper end of the chamber 22, while the lower end of the chamber wall rests in a recess formed in the bottom wall of the chamber 19, so as to preserve a proper relation of the parts when they expand owing to the intense heat. As shown in Fig. 3, this cover 22' has a downward projection fitting into the upper end of the chamber 22, to properly position the cover when it is re-applied after having been removed for the purpose of inspecting or cleaning the chamber 22 and the parts located at the bottom of said chamber. 100

Through the top wall of the chamber 19, 105 adjacent to the furnace, extends a gate 23

whose lower portion fits loosely into, and is guided in, a widened portion of the channel 18". The gate 23 is secured to a rod 23' by means of which it can be raised or lowered 5 to any desired position and secured in such position in any suitable way (not shown). In its lowermost position (shown in Fig. 3), the gate 23 will close the channel 18" and stop the flow of molten glass from the furnace, while in its raised position (Fig. 5), the gate will allow the glass to flow into the channel 21 and chamber 22. The normal level of the glass in the furnace may be as indicated at A in Fig. 3.

15 The supply channel 21 and the discharge chamber 22 form together a container for molten material whose admission to this container is, as just described, controlled by the gate 23, while its discharge through the 20 lower end of the chamber 22 is controlled by other means, as will be described later. This container is suitably heated by means of a burner 24, or other heating devices, registering with an opening 19' provided in the top 25 of the chamber 19. The heating gases emanating from, or produced by, this burner will circulate around the container 21, 22, so as to keep the glass contained therein or flowing therethrough at the desired degree 30 of temperature, and will then escape into the furnace through the upper outlet portion 18'. Another burner, 25, in registry with an opening 19" also provided in the top wall of the chamber 19 serves to heat the lower 35 portion of the gate 23 and surrounding parts, so as to enable the gate to be raised at the beginning of the operation. After the gate has been raised to the proper position, this burner 25 will be shut off.

40 The chamber 22 communicates at its lower end with a discharge nozzle 26 made of fire-clay or other refractory material (Figs. 3, 4, 6 and 7). While the opening in the nozzle 26 at the junction with the chamber 22 45 is circular, it is oblong at the lower portion where the walls of the opening are vertical, such lower portion of the opening being shown about twice as long as wide. Between this lower portion and the upper end, 50 the wall of the opening flares so as to form a gradual transition from the oblong to the circular shape. A comparison of Figs. 6 and 7, which are taken at right angles to each other, will make this clear. The nozzle 26 is supported by an annular flange 27' 55 on a plate 27 which itself is secured to the bottom plate 20 by means of screws 28 extending through recesses 27" in the plate 27 and screwing into the bottom plate 20.

60 These recesses are wide enough to allow one plate to be shifted laterally with respect to the other for the purpose of adjustment as will be described below. Washers 28' of large diameter interposed between the heads 65 of the screws 28 and the plate 27 will assist

in holding the plates together even if the plate 27 should have to be shifted to such an extent that the screws 28 will engage the side walls of the recesses 27". The opening in the bottom of the chamber 19 and in the 70 bottom plate 20, which receives the nozzle 26 and the flange 27', should be sufficiently larger than the nozzle 26 and flange 27' to leave an annular space for the purpose of the adjustment just referred to. 75

Set in a recess in the under side of the plate 27, and flush with said under side, is a small plate 29 having an opening of the same size and shape as, and registering with, the lower portion of the nozzle opening. 80 This plate 29, which in effect becomes part of the nozzle, is held in place by two metal strips 30 secured to the plate 27 by screws 30' and forming guides for a movable knife carrier 31, which normally closes the outlet 85 from the nozzle by lying close to the plate 29 against said outlet, and therefore also serves as a valve. The carrier 31, with its knife or blade 32, is adapted to be reciprocated along the guide strips 30 to and from the nozzle outlet, which, as described above, is of an oblong shape, in the direction of its longer axis, by the following device: At the end farthest away from the nozzle 26, the carrier is rigidly connected with one end 90 of a piston rod 33 having at its other end a piston 33' adapted to be reciprocated in a cylinder 34 which is carried by a lateral extension 27* of the plate 27 and is adjustable lengthwise in slots 27a of said extension. 95 The piston is actuated by admitting a fluid under pressure, such as steam or compressed air, to one or the other of its sides, through pipes 35, 36 communicating with the cylinder chambers 34', 34" respectively through 100 ports in the cylinder heads. The admission of the actuating fluid is controlled by a piston valve (Figs. 2 and 10) consisting of a cylinder 37 and a piston rod 38 having two pistons 38', 38" rigidly mounted thereon 105 at a distance from each other and dividing the interior of the cylinder into three chambers 37', 37" and 37*. The cylinder wall has three ports, the central port communicating with a pipe 39 through which the compressed fluid is admitted to the cylinder chamber 37", while the two side ports connect the interior of the cylinder with the pipes 35, 36 respectively. As these pipes 35, 110 36 serve at times as exhaust pipes (as will be described presently), the heads of the valve cylinder 37 are provided with a number of holes 37a, 37b leading to the outside and allowing the exhaust to escape into the 115 surrounding air. The side wall of the cylinder 34 has two ports one of which is located at a certain distance from one of the cylinder heads, while the other is located at the same distance from the other cylinder head. 120 These ports communicate with pipes 35', 36' 125 36 respectively. 130

respectively connected with the pipes 35, 36 at 35", 36". At a point between 35", 36" and the heads of the cylinder 34, the pipes 35, 36 are provided with by-pass check valves 40, 41 respectively, the detail construction of which is shown in Figs. 11 and 12 and is as follows: Into the valve casing 40 lead passages 40', 40", the former communicating with that portion of the pipe 35 which leads 10 to the cylinder 34, while the passage 40" communicates with the portion of pipe 35 leading to the cylinder 37. Passage 40' leads directly into a central chamber 40*, while between passage 40" and this chamber is 15 interposed a check valve 42 adapted to be lifted from its seat, the valve stem 42' being guided in a socket 43' provided in the screw cap 43. From the passage 40", another passage, 40^a, leads to the chamber 40*, this passage being throttled by a needle valve 44 screwing into the valve casing and provided at its outer end with a milled head 44', a screw cap 45 insuring a tight joint. The purpose of these by-pass check valves is to 20 prevent the piston 33' from striking too hard against the cylinder heads. When the compressed fluid is admitted, say to the cylinder chamber 34" through the pipe 36, the check valve in the valve casing 41 (corresponding to check valve 42 in the valve casing 40) having been lifted by the pressure, so that the fluid can pass unobstructed through the pipe 36, the piston 33' will be moved from the position shown in Fig. 7 25 toward the other end of the cylinder, expelling the exhaust in chamber 34' through the pipe 35' into the pipe 35 and cylinder chamber 37', from where it will escape to the atmosphere through ports 37^a. As soon as 30 the piston 33' has covered the port leading to the pipe 35', the fluid remaining in the cylinder chamber 34' will be compressed, being allowed to escape but slowly through the passage 40^a in the valve casing 40, and 35 an air cushion will thus be formed which will prevent the piston from striking hard against the cylinder head. When the piston is propelled in the other direction, the operation takes place in a similar manner. 40

As shown in Fig. 1, the piston valve cylinder 37 is rigidly secured to a stationary support 46. The piston rod 38 is connected by means of a screw 47 to one end of a rod 48 adapted to slide in a stationary bracket 49 secured to a base plate 50 by a screw 49'. At its other end the rod 48 is forked to receive a roller 51 (Fig. 2) mounted to turn in said forked end on a pin 51'. A coiled spring 52, one end of which engages the bracket 49, while the other end bears against a shoulder 48' on the rod 48, tends to push the forked end of the rod carrying the roller 51 away from the bracket 49 and thus the piston rod 38 will normally be in its outermost position, with the piston 38' against 45 the front head of the cylinder. Through a socket provided in the rod 48, at a point between its forked end and the shoulder 48', extends loosely a screw-threaded connecting member 53. Normally, this connecting member is held rigidly to the rod 48 by means of a washer 53' having a spherically-curved engaging surface, in conjunction with the similarly-curved head of the connecting members and nuts 53". The ends of the socket engaged by the washer 53' and by the head of the connecting member are of course curved so as to fit the said spherically-curved engaging surfaces. The connecting member 53 also extends loosely through a socket in a rod 54, but is normally held rigidly to said rod by means of washers 53' and nuts 53". The rod 54, similarly to the rod 48, carries at one end a roller 51", has a shoulder 54' engaged by a spring 52' and is adapted to slide in a bracket 55 secured to the base plate 50 by a screw 55'. Its other end is, however, not connected to a piston rod, but is preferably screw-threaded to receive nuts 54" which will limit its movement in one direction by engaging the bracket 49'. 50

The rollers 51, 51" will be engaged at times by cams on the machine in conjunction with which my discharge device is used. Thus the cam 56 may be on the rotary member 57 of a bottle-making machine of the well-known type in which a member carrying molds and various other mechanisms rotates about an upright axis. In Fig. 1, the left-hand margin line of the drawing may be assumed to indicate this upright axis. It will now be clear from the above description that a sliding movement of the rod 48 toward the cylinder 37 will cause, by means of the pipe connections and cylinder arrangements, the knife carrier or valve 31 to be withdrawn from engagement with the nozzle 26, thus allowing the molten material contained in the nozzle and container 21, 22 to be discharged through the nozzle. On the other hand, a movement of the rod 48 away from the cylinder 37 will cause the carrier 31 to again close the nozzle outlet. The purpose of having two rollers, 51 and 51", mounted at an adjustable distance from each other, is to be able to regulate the time during which the nozzle is open and thereby vary the amount of molten material to be discharged every time the carrier is withdrawn from the nozzle, without changing the length of the cams engaging the rollers. When it is desired to alter the amount of molten material discharged each time, the nuts 53" will be loosened and the rollers adjusted to the proper distance from each other. The nuts 53" are then again tightened, so that the rods 48, 54 will be rigidly connected by the connecting member 53. Any action on the roller 51" will of course 55 60 65 70 75 80 85 90 95 100 105 110 115 120 125 130

also actuate the rod 48. The bracket 55 in which the rod 54 slides, is of course mounted on the base plate 50 adjustably, and for this purpose the head of the screw 55' is held in a groove 50' in the base plate 50, in which it can slide lengthwise with the bracket 55, after the nut on the upper end of the screw 55' has been loosened. As soon as this nut is again tightened, the screw 55' and bracket 55 will be rigidly connected with the base plate 50. The rods 48, 54 being almost parallel and their sliding movement only small, the slight play provided in practice will be sufficient to enable them to slide readily in the brackets 49, 55, without any danger of binding.

The construction of the knife 32 and its carrier 31 has been shown in detail in Figs. 14 and 15, and the cutting operation has been illustrated diagrammatically in Figs. 16 and 17. It will be seen from these views that the cutting edge of the knife 32 is made in such a way that at the beginning of the cutting operation it will conform to the outline of the nozzle at its round end and will therefore engage at once the molten material over the whole width of the nozzle opening (see Fig. 16). As the quantity of molten material to be withdrawn each time is relatively small, this feature is of great importance, particularly when taken in conjunction with the fact that the nozzle opening is oblong. As stated above, the knife carrier moves in the direction of the longer axis of the nozzle opening. The width of the cut will therefore remain practically constant during the entire forward movement of the cutter. The result will be an elongated body of molten material of practically uniform thickness throughout its length. This is very desirable in case my device is used in connection with a glass furnace and a bottle-making machine. The molten glass, owing to its viscosity, will not flow out of the nozzle quickly, but will hang down at first, as shown in Fig. 17 by the dotted line α . The knife, as it progresses, will then cause the glass to assume the elongated shape referred to above and also shown in Fig. 17.

The blade 32 is secured to the carrier 31 by means of a clamp 58 and screws 58', the clamp being spaced from the carrier by liners 58''. The blade is also dovetailed into the forked end of the carrier, as in Fig. 14, and at the forward end of the blade its side faces are not only converged transversely, but longitudinally as well. The corresponding longitudinally converging guide portions of the carrier act as a stop to arrest the blade when it is being adjusted, in the position in which it is flush with the upper surface of the carrier (Fig. 15). In regrinding the blade, I remove a portion of its top surface to uniform depth and then reinsert the blade after having removed one or more

liners. The carrier is preferably provided with passages through which a cooling fluid admitted at 31' and escaping at 31'' will circulate to prevent the carrier and blade from being heated too strongly by the glass. In view of the reciprocating motion of the carrier, the inlet 31' and outlet 31'' should of course be connected to flexible pipes.

To insure proper engagement of the blade 32 with the plate 29 (forming part of the nozzle), I provide at each side of the blade levers 31* pivoted on brackets 27^b secured to the plate 27 (Figs. 6, 7, and 9). These levers carry in suitable sockets, rollers 31^a and are pressed upwardly by springs 27^c 80 sliding on rods 27^d carried by the plate 27. The rollers 31^a will thus always press the carrier 31 with the blade 32 firmly against the nozzle opening, while at the same time allowing said carrier and blade to move freely along the guides 30. In Fig. 9^a I have shown a modification of the device, in which the rollers 31^a are pressed against the carrier 31 by counterweights 31^b secured to extensions on the other sides of the pivots 90 of the levers 31*. As shown in Fig. 7, a small plate 59 is secured to the plate 27 between the guides 30, at a point near the end of the travel of the cutting edge. On its side facing this cutting edge, the plate 59 has a convex edge corresponding to the outline of the cutting edge (Fig. 14); this convex edge of the plate 59 is also beveled for the purpose of directing downward any molten material which may be forced against 100 that side by the knife or blade.

To the underside of the plate 27 are secured, by means of screws 60', guides 60 extending in a direction transverse to that of the cutter guides 30. Along these guides 60 are adapted to travel rollers 61 connected by means of pins 61' and brackets 62' with a transfer funnel or blank former 62 having a through-passage 62'' adapted to register with the nozzle opening. At its lower, discharge end, this passage is preferably cylindrical, while the upper portion is preferably, but not necessarily, widened or flaring so as to have at its upper extremity an elongated shape corresponding approximately to that of the nozzle opening, but considerably larger than the latter. The term "funnel," as used by me, is not to be interpreted as necessarily restricted to a structure with a flaring passage. The upper, receiving end of the transfer funnel is, in the construction shown in the drawings, located at a sufficient distance from the nozzle opening, so as not to interfere with the operation of the knife and its carrier. On that side, however, which lies farthest away from the knife, that is, the side toward which the knife moves in cutting the glass, the transfer funnel has an extension 62* reaching to within close proximity of the 115 120 125 130

plate 27. This extension flares upwardly and outwardly and its inner face thus forms a continuation of the upper flaring portion of the funnel. The knife, at the end of its 5 cutting stroke, forces the depending glass body, or the upper portion of such body, toward the extension 62* along which this glass body will slide down into the passage 62" and from the delivery end of this passage 10 to the mold or other receptacle arranged underneath the funnel and in registry therewith. The axis of the transfer funnel or blank former will of course be in line with the axis of the mold or other receptacle 15 which is to receive the glass, but preferably slightly out of line and forward of the axis of the nozzle opening, so as to properly receive and direct the lump of glass. In Fig. 1, I have shown as example a mold 20 63 in position underneath the transfer funnel. Such mold may be connected with the rotary member 57 of the bottle-making machine in any well-known or approved manner. Preferably, I employ a machine of the 25 type in which the member 57 rotates continuously and in which provision is made for arresting the travel of the mold at the time it receives its charge. The inner surfaces of the tapering portion of the funnel and of its 30 extension are preferably made very smooth, for instance polished, so as to prevent any particles of glass from sticking thereto.

The funnel or blank former 62 is preferably made integral with an outer straight wall 62^a, forming with the interior wall of the funnel a jacket through which a cooling medium, such as water, can be circulated. This cooling medium is admitted at 62^b and will effectively cool the funnel which is 35 liable to become very hot owing to the passage therethrough of the molten glass.

As described above, the knife cuts off, and shapes to a certain extent, an elongated body of glass of practically uniform width and 40 thickness. By coming in contact with the flaring portion of the funnel and from there sliding down through the comparatively narrow cylindrical portion, this glass is not only directed properly into the mold or other receptacle into which it is to be transferred, but it is also formed or shaped in said funnel into a perfectly cylindrical body and thus delivered to the mold or other receptacle in the most desirable shape and manner. 45

The cooling medium circulating around the funnel or blank former also serves to cool to a certain extent the body of glass passing therethrough, it being understood that the glass has been kept very hot up to the moment it issues from the nozzle. This cooling 50 action on the glass is effected quite uniformly owing to the fact that the elongated body of glass on its way down through the narrow straight portion of the funnel, completely fills this portion of the funnel 55 and therefore is in contact therewith all around.

The transfer funnel, as described above, is suspended from the guides 60 by means of the rollers 61. This is for the purpose of 60 moving it out of its position in registry with the nozzle opening, when desired, and of bringing into position under the nozzle a discharge member 64 shown in Figs. 1, 6, 7 and 8. This discharge member, in the example 65 shown, has a downwardly and rearwardly inclined open channel, and is conveniently made integral with the transfer funnel 62, the bottom wall of the discharge member or channel forms part of the outer wall of the 70 cooling jacket; the channel is also conveniently used as an overflow for the cooling medium circulating through said jacket, which overflow takes place through a series of holes 64' provided in the channel in a 75 projection near its upper portion (Figs. 6 and 8). Preferably, the following means are used to move the transfer funnel 62 out of position and the discharge channel 64 into position in registry with the nozzle opening: To the discharge channel 64 is secured rigidly, by means of screws or otherwise, a U-shaped bracket 65 connected rigidly with one end of a rod 66 provided at its other end 80 portion with a screw-thread 66' in engagement with an internal screw thread on a bevel gear 67 supported from the bottom plate 20. In mesh with this gear 67 is another bevel gear, 68, mounted on a shaft 69 also supported from the bottom plate and having at its other end a hand wheel 70 (Figs. 1 and 13). By turning the hand wheel 70, the gear 68 will cause the gear 67 to revolve, and this, by means of the internal screw 85 thread will cause the rod 66 to move lengthwise of its axis, imparting this movement to the discharge member 64 and transfer funnel 62 which, by means of the rollers 61 traveling in the guides 60, will be brought from the position shown in full lines in Fig. 90 95 6, to the position shown in dotted lines in said figure, in which latter position the discharge channel 64 will register with the nozzle opening. Small plates 60" secured to the ends of the guides 60, will stop the rollers in their extreme positions.

The purpose of making the transfer funnel or blank former movable and of providing a discharge member to take at times the 100 place of the funnel, is as follows: At the end of the operation, that is, when it is no longer desired to withdraw molten glass from the furnace and to transfer it into molds or other receptacles, the gate 23 having been closed, the container 21, 22 will still contain a certain amount of molten glass. If this glass were allowed to stand in the container for any length of time, it would cool and become hard, especially in the lower 105 part of the container next to the nozzle, even 110

115

120

125

130

if the container were kept heated continuously by means of the burner 24. The nozzle opening would become clogged and it might even become impossible to withdraw the knife carrier from the opening when it is desired to again begin the operation of the machine. For this reason the discharge member 64 will be moved into position under the nozzle opening, the latter will be opened, 10 and the glass contained in the chamber 22 and channel 21 will flow out readily owing to the inclined bottom of the latter, and will drop into the discharge member, where it will cool by coming in contact with the water flowing down in the discharge channel from the overflow of the jacket. An inclined channel 71 (Fig. 1) forming a continuation of the discharge member 64, will receive the glass and water from the latter and deliver 15 it into a tank (not shown) where the glass will be fully cooled and from where it can be removed and used over again.

As shown in the drawings, the chamber 19 with the parts carried thereby or connected therewith, is preferably supported or suspended from the furnace in the following manner: On top of the furnace rests an I-beam 72 held in place by upright I-beams 73 customary in constructions of this character. To this I-beam 72 are fastened the ends of two inclined suspension or bracing rods 74, preferably divided into two parts connected by turnbuckles 74'. The other ends of these rods are hooked-shaped and 20 extend through holes or eyes provided in the upper ends of uprights bars 75 extending at the sides of the chamber 19; the lower ends of these bars 75 are provided with holes to receive the hook-shaped ends of 25 forwardly converging lateral bracing rods 76, preferably horizontal and divided into two parts connected by turnbuckles 76'. The other ends of the bracing rods 76 are secured to the I-beams 73. The bars 75 are 30 riveted or otherwise secured rigidly to the flange 20' on the bottom plate 20 and to straps 77, 78 extending around the chamber 19, at its upper and middle portions respectively. Another upright bar, 79, is provided 35 at the front end of the chamber 19, and also connected to the plate 20 and the straps 77, 78. Angle irons 80 connect the straps 77, 78 and the plate 20 at their respective ends adjacent the furnace.

It will be seen that this mode of suspending the chamber 19 will enable me to adjust it properly with respect to the mold or other receptacle to which the glass is to be transferred. It may not always be possible to 40 construct the chamber 19 with sufficient accuracy, especially in view of the fact that the expansion of the chamber owing to the intense heat to which it will be subjected, has to be taken into account. By means of 45 the bracing rods 74 and turnbuckles 74' the

chamber 19 can be leveled properly, while by means of the bracing rods 76 and turnbuckles 76' it can be swung slightly to one side or the other, until the nozzle outlet is in its proper position. A further adjustment of the nozzle toward or from the furnace 70 18, if desired, is possible by shifting the plate 27 carrying said nozzle, with respect to the bottom plate 20, after having loosened the screws 28 holding the plates 27 and 20 together. After the nozzle has been brought to its proper position, the screws 28 are again tightened. 75

As shown in Fig. 3, the chamber 19 is provided with a socket 19* extending into the inclined channel 21, for the insertion of a pyrometer (not shown), by means of which the temperature of the glass flowing through the supply channel 21 can be ascertained. 80

While my apparatus has been shown and described in connection with a machine for making bottles or similar articles, it may be used wherever it is desired to discharge from a furnace molten material into molds or other receptacles for further treatment. 85

No claim is made herein to the adjustably timed actuation of the feeder in synchronism with the movement of the mold table 57, or to the specific structure for producing such timed actuation. These features are claimed in the copending application for Letters Patent, Serial No. 76,534, filed December 19, 1925 as a division of the present application. 90

Various modifications may be made without departing from the nature of my invention as defined by the appended claims. 100

I claim:

1. In a device for discharging molten material, a nozzle adapted to receive molten material, means movable adjacent to said nozzle, for controlling the discharge of material therefrom, a funnel movable independently of said means and transversely of its path of motion, into and out of registry 105 with said nozzle and adapted to receive molten material from said nozzle, and a discharge member movable in unison with the funnel and adapted to register with the nozzle when the funnel is moved out of 110 registry with the nozzle.

2. In a device for discharging molten material, a furnace provided with an opening for the exit of said molten material, a casing located exteriorly of the furnace adjacent 120 to said opening and provided with a downwardly inclined channel the upper end of which communicates directly with said opening at the level thereof, a nozzle connected with the lower end of said channel, means for cutting off the supply of molten material at the upper end of said channel directly adjacent to said exit opening of the furnace, and a cutter movable adjacent to the outlet 125 of the nozzle. 130

3. In a device for discharging molten material, a nozzle adapted to receive molten material, means movable horizontally adjacent to said nozzle, for controlling the discharge of material therefrom, a funnel movable independently of said means, in a horizontal path transverse to that of said means, into and out of registry with said nozzle and adapted to receive molten material from said nozzle, and a discharge member movable in unison with said funnel and adapted to register with the nozzle when the funnel is moved out of registry with the nozzle.
4. In a device for discharging molten material, a nozzle, means for conveying the molten material thereto, a cutter mounted to slide directly under the outlet of the nozzle, and a transfer funnel arranged to receive the material severed by said cutter and provided with an upward extension on the side toward which the cutter slides on its active stroke.
5. In a device for discharging molten material, a nozzle having an outlet of oblong outline, means for conveying the molten material to said nozzle, and a cutter movable adjacent to the nozzle outlet and lengthwise thereof.
6. In a device for discharging molten material, a casing provided with an upright discharge chamber, means for supplying material to said chamber between its top and its bottom, a nozzle at the bottom of said chamber, and a removable cover provided with a downward projection fitting into the upper end of said chamber, normally closing the latter.
7. In a device for discharging molten material, a nozzle, means for conveying the molten material thereto, means for cutting the material adjacent to the nozzle outlet, a transfer funnel provided with a channel for the passage of a cooling medium and movable into registry with the nozzle outlet to receive the severed material, and a discharge member movable in unison with said funnel and likewise adapted for registry with the nozzle outlet, said discharge member being constructed to receive the cooling medium after its passage through the channel of the funnel.
8. In a device for discharging molten material, a container for the molten material, a receiver for the material discharged from said container, and a downwardly contracted nozzle interposed between the said container and receiver and carried by the container and adjustable transversely relatively to said container.
9. In a device for discharging molten material, a casing provided with an upright discharge chamber, means for supplying material to said chamber between its top and its bottom, a nozzle at the bottom of said chamber, and a removable cover, located in line with said nozzle, for normally closing the upper end of said chamber.
10. In a device for discharging molten material, a receptacle adapted to contain a supply of molten material and provided with an opening through which said material may pass out, a casing provided with a discharge chamber adapted to receive material from said opening, a gate controlling said opening, and a burner set in said casing on the outside of the gates and directed toward the outer face of said gate to heat the same.
11. In a device for discharging molten material, a container for molten material, a laterally-adjustable nozzle therefor, and a laterally-adjustable plate having a flange on which said nozzle rests, to carry the nozzle laterally with the plate when the latter is adjusted.
12. In a device for discharging molten material, a container for molten material, said container having an outlet and an opening or clearance adjacent thereto, and a laterally-adjustable nozzle arranged adjacent to said outlet and projecting into said opening with sufficient clearance for the lateral adjustment of the nozzle, so that the walls of the opening will form stops to limit the lateral movement of the nozzle.
13. In a device for discharging molten material, a container for molten material, said container having an outlet, a movable cutter for severing the stream of material issuing from said outlet, a piston operatively connected with said cutter, a cylinder in which said piston reciprocates, said cylinder having ports at both ends, and intermediate ports controlled by said piston, another cylinder having a connection with a source of pressure supply, pipes connecting said second cylinder with the ports at the ends of the first-named cylinder, a piston located in the second-named cylinder and controlling the admission of fluid under pressure from said cylinder to one or the other of said pipes, additional pipes leading from each of said intermediate ports to the pipe connected with the adjacent end port, and a check valve located in each of the first-named pipes between the respective end port and the connection of said pipe with the corresponding additional pipe, said check valve opening toward the first-named cylinder and being provided with a throttled by-pass, whereby a cushioning effect is obtained at each end of the stroke of the respective piston.
14. In a device for discharging molten material, a container for molten material, said container having an outlet, a movable cutter for severing the stream of material issuing from said outlet, a piston operatively connected with said cutter, a cylinder in which said piston reciprocates, said cylinder having ports at both ends, and intermediate

- ports controlled by said piston, separate pipes connected with said end ports, means for admitting a fluid under pressure to one of said pipes or the other, additional pipes leading from each of said intermediate ports to the pipe connected with the adjacent end port, and a check valve located in each of the first-named pipes between the respective end port and the connection of such pipe with the corresponding additional pipe, said check valve opening toward said cylinder and being provided with a throttled by-pass, whereby a cushioning effect is obtained at each end of the piston stroke.
15. In a device for discharging molten material, a container provided with an outlet, a cutter-carrier movable adjacent to said outlet and provided with a forked end facing said outlet, and a cutter secured to said forked end.
20. In a device for discharging molten material, a container provided with an outlet, a cutter-carrier movable adjacent to said outlet and provided with a forked end facing the outlet, and a cutter having beveled edges fitted into said forked end.
25. In a device for discharging molten material, a container provided with an outlet, a cutter-carrier movable adjacent to said outlet and forked at the end nearest the outlet, and a cutter secured to said forked end, the engaging faces of the cutter and of the cutter-carrier converging both forwardly longitudinally and downwardly transversely of the fork members.
30. In a device for discharging molten material, a container provided with an outlet, a cutter movable adjacent to said outlet, a lever, a roller carried by said lever and engaging the cutter on the side facing away from the outlet, and means for pressing said lever toward said outlet.
35. In a device for discharging molten material, a container provided with an outlet, a cutter movable adjacent to said outlet and provided with a concave edge facing the outlet, and a stationary member located adjacent to said outlet and provided with a convex edge facing said concave cutter edge and cooperating therewith.
40. In a device for discharging molten material, a container provided with an outlet, a cutter movable adjacent to said outlet and provided with a concave edge facing the outlet, and a stationary member located adjacent to the outlet on that side thereof which the cutter reaches last in its operative movement, said stationary member having a convex edge directed toward, and cooperating with, the concave edge of the cutter, and beveled to flare away from the outlet.
45. In a device for discharging molten material, a container provided with an outlet having an upright axis, a cutter movable horizontally adjacent to said outlet, and a transfer funnel located beneath said outlet, the axis of said transfer funnel being out of line with the axis of the outlet, and located on the far side thereof, with reference to the active movement of the cutter.
50. In a device for the discharge of molten material, a container provided at its lower portion with an outlet having an upright axis, a cutter movable horizontally adjacent to said outlet, and a member adapted to receive the molten material severed by said cutter, the axis of said member being out of line with that of the outlet, and located on the far side of said outlet axis, with reference to the direction in which the cutter moves during the severing operation.
55. In a device for discharging molten material, a container provided with an outlet, a jacketed transfer funnel movable into and out of operative relation to said outlet, and a discharge member connected to said transfer funnel to move in unison therewith and to register with the outlet at times when the transfer funnel is out of registry therewith, the jacket of the funnel being provided with overflow openings leading into the said discharge member.
60. In a device for discharging molten material, a container provided with an outlet, a transfer funnel and a discharge member movable in unison and adapted to come alternately into operative relation to said outlet, and a stationary channel adapted to register with the discharge member at the time said member is in operative relation to the container outlet.
65. In a device for discharging molten material, a furnace, a nozzle, means for conveying material from said furnace to said nozzle, and means permitting said nozzle to be adjusted laterally toward and from the furnace.
70. In a device for discharging molten material, a furnace, a nozzle, means for conveying material from said furnace to said nozzle, and means permitting said nozzle to be adjusted toward and from the furnace, and also laterally of the direction of the first-named adjustment and vertically, to vary the position of the nozzle outlet and of the stream discharged therefrom.
75. In a device for discharging molten glass, the combination of a container provided with a discharge outlet, shearing means for cutting the discharged glass, a funnel for receiving the discharged glass, said funnel being movable into and out of registry with said outlet, means for circulating a cooling fluid around said funnel, and a discharge member movable in unison with said funnel and likewise adapted for registry with said outlet, the said discharge member being arranged to receive said cooling fluid after it has passed in cooling relation to said funnel.
80. In a device for discharging molten material, a container provided with an outlet, a cutter-carrier movable adjacent to said outlet and provided with a forked end facing said outlet, and a cutter secured to said forked end.
85. In a device for discharging molten material, a container provided with an outlet, a cutter-carrier movable adjacent to said outlet and provided with a forked end facing the outlet, and a cutter having beveled edges fitted into said forked end.
90. In a device for discharging molten material, a container provided with an outlet, a cutter-carrier movable adjacent to said outlet and forked at the end nearest the outlet, and a cutter secured to said forked end, the engaging faces of the cutter and of the cutter-carrier converging both forwardly longitudinally and downwardly transversely of the fork members.
95. In a device for discharging molten material, a container provided with an outlet, a transfer funnel and a discharge member movable in unison and adapted to come alternately into operative relation to said outlet, and a stationary channel adapted to register with the discharge member at the time said member is in operative relation to the container outlet.
100. In a device for discharging molten material, a furnace, a nozzle, means for conveying material from said furnace to said nozzle, and means permitting said nozzle to be adjusted laterally toward and from the furnace.
105. In a device for discharging molten material, a furnace, a nozzle, means for conveying material from said furnace to said nozzle, and means permitting said nozzle to be adjusted toward and from the furnace, and also laterally of the direction of the first-named adjustment and vertically, to vary the position of the nozzle outlet and of the stream discharged therefrom.
110. In a device for discharging molten material, a furnace, a nozzle, means for conveying material from said furnace to said nozzle, and means permitting said nozzle to be adjusted toward and from the furnace, and also laterally of the direction of the first-named adjustment and vertically, to vary the position of the nozzle outlet and of the stream discharged therefrom.
115. In a device for discharging molten glass, the combination of a container provided with a discharge outlet, shearing means for cutting the discharged glass, a funnel for receiving the discharged glass, said funnel being movable into and out of registry with said outlet, means for circulating a cooling fluid around said funnel, and a discharge member movable in unison with said funnel and likewise adapted for registry with said outlet, the said discharge member being arranged to receive said cooling fluid after it has passed in cooling relation to said funnel.
120. In a device for discharging molten material, a container provided with an outlet having an upright axis, a cutter movable horizontally adjacent to said outlet, and a transfer funnel located beneath said outlet, the axis of said transfer funnel being out of line with the axis of the outlet, and located on the far side thereof, with reference to the active movement of the cutter.
125. In a device for discharging molten material, a container provided at its lower portion with an outlet having an upright axis, a cutter movable horizontally adjacent to said outlet, and a member adapted to receive the molten material severed by said cutter, the axis of said member being out of line with that of the outlet, and located on the far side of said outlet axis, with reference to the direction in which the cutter moves during the severing operation.
130. In a device for discharging molten material, a container provided with an outlet, a cutter-carrier movable adjacent to said outlet and provided with a forked end facing said outlet, and a cutter secured to said forked end.

28. In a device for discharging molten glass, the combination of a container provided with a discharge outlet, shearing means for cutting the discharged glass, a funnel for receiving the discharged glass, said funnel being movable into and out of registry with said outlet, means surrounding said funnel and defining a chamber for the circulation of cooling fluid, and a discharge member movable in unison with said funnel and likewise adapted for registry with said outlet, the said discharge member and the said chamber being connected by an opening through which the cooling fluid may pass from said chamber to said discharge member.
29. In combination, a glass container having a discharge outlet, a combined trough and funnel, each mounted for movement into registry with said outlet, a cooling jacket for said funnel, and means for conveying the cooling medium from the funnel to the trough.

In testimony whereof I have signed this specification.

MERTON A. STEELMAN.
